UNITED STATES PATENT OFFICE.

ARTHUR J. BACKER, OF SYRACUSE, NEW YORK.

FOLDING TABLE.

1,132,061.

Specification of Letters Patent. Patented Mar. 16, 1915.

Application filed May 9, 1912. Serial No. 696,188.

To all whom it may concern:

Be it known that I, ARTHUR J. BACKER, of Syracuse, in the county of Onondaga, in the State of New York, have invented new and useful Improvements in Folding Tables, of which the following, taken in connection with the accompanying drawings, is a full, clear, and exact description.

This invention relates to certain improvements in folding tables for camp outfitts and similar uses and refers more particularly to the frame for supporting any suitable folding or rigid top.

The main object is to provide a light and comparatively inexpensive portable frame capable of supporting relatively heavy loads when adjusted for use and also adapted to be folded into compact space for transportation and storage.

Another object is to provide the frame with suitable legs capable of being folded within the surface of the end pieces of the frame and held in such position concealed from view when the frame is folded to its minimum size.

Other objects and uses relating to specific parts of the device will be brought out in the following description.

In the drawings—Figure 1 is a perspective view of my improved frame adjusted for use. Fig. 2 is a perspective view of the same frame in its folded condition. Fig. 3 is an inverted plan of one end of the frame in its extended position except that the legs are folded into the groove in one of the end pieces. Fig. 4 is a lengthwise sectional view through one of the end pieces showing the manner of folding the legs into the groove provided therefor. Fig. 5 is an enlarged transverse sectional view through one of the end pieces taken on line 5—5 Fig. 1.

As illustrated in the drawings, the folding frame comprises opposite parallel side pieces —1— and —2—, opposite parallel end pieces —3— and —4— and folding legs —5—, the side bars being divided transversely midway between the ends, all of which parts may be made of wood or sheet metal for lightness and strength and are hinged to each other in a manner herein-after described so as to constitute a rectangular frame when adjusted for use or may be folded into the position shown in Fig. 2. The side and end bars are preferably of the same cross sectional form and size usually rectangular and of greater vertical depth

than transverse thickness so as to better resist the weight of any load which may be placed thereon. The joining ends of the side and end bars are hinged together in the same plane by vertical pivots —6— and —7—, while the side bars —1— and —2— are divided in the same transverse plane to form alined sections —1'— and —2'—, the meeting ends of the sections of each side being hinged by horizontal transverse pivots —9—, thereby dividing the frame into opposite U-shaped end sections each adapted to swing upon the other about the co-axial pivots —9— so that when folded to the position shown by dotted lines in Fig. 1, the pivots —6— and —7— at one end of the frame will be brought into exact co-axial alinement with the corresponding pivots —6— and —7— at the opposite end. The axes of the pivots —6— are preferably in the same plane as the inner faces of the sides —1— and ends —2— so as to allow the side sections —1'— to be folded against the inner face of the adjacent end section. The axes of the pivots —7— are preferably located at the intersection of the planes of the outer faces of the side bars —2'— and end bars —3— so as to allow the side bars —2'— to fold against the outer faces of the adjacent end bars as shown more clearly in Fig. 2.

It will be observed upon reference to Fig. 1 that the axes of the pivots —9— connecting the sections of the side bars —1— and —2— are located in the plane of the lower edges of said sections and also in the plane of the meeting edges —8— which are disposed at right angles to the plane of the upper edges of the bars so as to abut against each other when the frame is adjusted for use to hold the bars in a substantially horizontal position against downward depression under load, and at the same time permitting the end halves of the frame to be folded one upon the other as shown by dotted lines in Fig. 1.

The distances between the axis of the hinge —9— connecting the side sections —1'— and vertical axes of the hinges —6— connecting the opposite ends of the side bar —1— with the end bars —3— and —4— are equal and in like manner the distances between the axis of the hinge —9— connecting the side sections —2'— and vertical axes of the hinges —7— connecting the ends of the side bar —2— with the end bars are equal

so that when the opposite end halves of the frame are folded one upon the other in the manner shown by dotted lines in Fig. 1, the axes of the hinges —7— and also the axes 5 of the hinges —6— will be in co-axial alinement, thus permitting the side sections —1'— to be folded against the inner sides of the end sections —3— and —4— and also permitting the side sections —2'— to be folded 10 against the outer side of the same end sections to the position shown in Fig. 2 when the legs are folded as presently described.

In order that the legs may be folded within the surface area of the end pieces and 15 concealed from view when the frame is folded to the position shown in Fig. 2, each of the end pieces —3— and —4— is provided with a lengthwise slot or groove —10— opening upwardly from its underside a sufficient 20 distance to receive both of the adjacent legs therein, said legs being pivoted at —11— to their respective end pieces near the ends of the slots, which latter is nearly as long as the end piece, said legs being preferably 25 tapered for strength and are preferably of the same width as the slots so as to fit snugly therein and at the same time to be free to fold or unfold into and out of the groove —10—. The ends of the slot are 30 slightly inclined downwardly and outwardly to form stop shoulders —12— against which the legs are adapted to abut when unfolded to the position shown in Fig. 1, thereby standing in a slightly inclined position to brace the table against lateral movement, and at the same time tending to hold 35 the legs against the shoulders.

It will be seen upon reference to Figs. 1 and 3 that the side sections —2'— extend 40 across the adjacent ends of the end sections and that the end faces of the end sections are flat and disposed at right angles to the main bodies of said sections so as to abut against the inner faces of the side sections 45 —2'— to additionally brace the frame when adjusted for use.

The hinge connections —6— are constructed to allow the side sections —1'— to be swung through an arc of at least 90° and 50 in this particular instance 180° to and from the inner face of the adjacent end sections

when the halves of the frame are folded one upon the other but the hinge connections —7— between the side sections —2'— and end sections —3— and —4— are constructed to allow the sections —2'— to swing through an arc of 270° or three-fourths of a circle to and from the outer faces of the end sections —3— and —4— under the same conditions, this operation being brought about by positioning the axes of the hinges —6— at the intersection of the inner faces of the side sections —1'— and end sections —3— and —4— and also by positioning the axes of the hinges —7— at the intersection 60 of the outer faces of the side sections —2'— and end sections —3— and —4—.

The details of construction and operation of my invention have been fully set forth in the foregoing description taken in connection with the accompanying drawings but it will be evident that these details may be varied somewhat without departing from the spirit of such invention.

What I claim is:

1. A folding rectangular table-frame having horizontally swinging hinge joints at its four corners and vertically swinging hinge joints midway between its ends, the pivots of the corner joints at one side being 80 located at the intersections of the inner faces of the adjacent portions of the sides and ends of the frame while the joints at the opposite corners are provided with abutting shoulders inside their pivots.

2. A folding rectangular table-frame having horizontally swinging hinge joints at its four corners and vertically swinging hinge joints midway between its ends, said vertically swinging joints having abutting 90 shoulders above their pivots, the pivots of the corner joints at one side being within the frame bars while the pivots of the opposite corner joints are outside of the frame bars.

In witness whereof I have hereunto set my hand on this 3d day of May 1912.

ARTHUR J. BACKER.
